UNITED STATES PATENT OFFICE.

JOHN V. RICE, JR., OF CHESTER, PENNSYLVANIA.

ECCENTRIC VALVE-GEAR.

SPECIFICATION forming part of Letters Patent No. 399,081, dated March 5, 1889.

Application filed October 4, 1888. Serial No. 287,191. (No model.)

To all whom it may concern:

Be it known that I, JOHN V. RICE Jr., a citizen of the United States, and a resident of Chester, in the county of Delaware and State 5 of Pennsylvania, have invented certain new and useful Improvements in Eccentric Valve-Gears; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a representation of this invention and is a vertical section. Fig. 2 is partly a front view and partly a cross-section. Figs. 3 and 4 are details. Fig. 5 is a modification.

20 The invention relates to improvements in single eccentric valve-gear for steam-engines; and it consists in the construction and novel combination of parts, as hereinafter set forth.

The invention is intended more particularly 25 for use in connection with engines having three cylinders. It is evident, however, that the device is adapted for use in connection with any engine, and the object is to provide a valve of simple construction that is easily 30 repaired should it become broken.

Referring to the drawings, A designates the steam-chambers, and B the exhaust-chamber.

C is the main driving-shaft, having the crank D thereon within the chamber B, and having 35 bearings a a'.

E represents the valve eccentric, having the integral sleeve F, fitting loosely on the main shaft, as shown. The outer sleeve, b, oscillates on sleeve F, and is provided with the annular groove d for engaging the collar G, which has the arms e extending outwardly 40 through bearings f in the chamber-head. The outer ends of said arms e are threaded and provided with a nut to secure the transverse 45 bar H thereon.

I is a hand-lever fulcrumed at one end to the outstanding arm J, and provided at a convenient point with the set-bolt g, which moves in the arc slot h in the arm i. The lever may 50 thus be secured to hold the eccentric in the

desired position on the main shaft, the said lever being connected to the transverse bar H by the pivoted link k.

The sleeve F is provided with diametrically-opposite longitudinal slots l, and a pin, m, 55 preferably threaded at its upper end, passes through a threaded opening in the sleeve b and through the slots l, projecting into the recesses n on the main shaft. The recesses n on each side of the shaft cross each other 60 centrally and obliquely to the direction of the shaft.

In operation when the lever is pulled outwardly the end of the pins m traverse the oblique recesses in the shaft, which changes the 65 position of the eccentric.

It is obvious that screw-bolts operated by gearing, as shown in Fig. 5, may be substituted for the lever and its connections with the collar G without materially changing my invention. 70

In order to facilitate the working of the parts, each pin m carries on its inner end the spiral form-block v, which engages the oblique slot of the shaft, and next to this block 75 is provided the straight block z, which engages the slot of the sleeve of the eccentric.

Having described my invention, what I claim, and desire to secure by Letters Patent, 80 is—

The eccentric valve-gear for steam-engines, consisting of the eccentric having the sleeve fitting loosely on the main shaft and having diametrically-opposite longitudinal slots, the outer sleeve having applied thereto means 85 for the movement of the valve, said main shaft having oblique crossing recesses therein, and the pins or pivots connected to the outer sleeve and passed through the slots in the inner sleeve, and having spiral form of blocks 90 engaging with the oblique crossing slots of the main shaft, substantially as and for the purpose set forth.

In testimony whereof I affix my signature in presence of two witnesses.

JNO. V. RICE, JR.
